OBSTETRIC BED

Arthur J. Logie, Westfield, Mass., assignor of one-half to Thomas T. Logie, Bridgeport, Conn.

Application May 7, 1935, Serial No. 20,184

16 Claims. (Cl. 311—7)

This invention relates to obstetric beds.

An object of the present invention is to provide an obstetric bed in which the patient may lie comfortably in outstretched or any desired position just before delivery and yet may assume and be moved to natural and convenient delivery position without being lifted from the bed or pulled over the mattress or the part of the bed on which she is lying.

10 An important feature of this invention is the provision of an obstetric bed divided substantially midway of its length to provide a head section for supporting the portion of the patient's body including and above the buttocks and a foot section for supporting the lower limbs of the patient, which sections are mounted on a frame for relative movement so that the head section may be moved to the foot-end of the bed just prior to delivery, and in which position easy access to the patient is had by the attending physician both for natural delivery and for those assisted by instruments.

20 Another feature of this invention is the provision on the head section of stirrups which are normally out of the way, but which may be swung into operative position to support the feet of the patient with the legs flexed at the knees, while the head section with the patient lying thereon is moved to and rests in delivery position.

25 Another feature of this invention is the provision on the head section of means for assisting in holding the legs of the patient spread apart in desired position.

30 A still further feature of the present invention is the provision on the head section of pull cords having suitable handles, against which the patient may strain during delivery.

35 And yet another feature of the present invention is the provision of a treadle and operative connections to the foot section of the bed whereby the foot section may be conveniently depressed below the plane of the head section so that the head section may be moved toward the foot of the bed into superposed relation over the foot section.

40 An extremely advantageous feature of the present invention is the provision of an obstetric bed having a head section movable toward the foot section into delivery position, and having the frame of the bed so constructed as not to obstruct passage between the side rails of the bed of an attending physician or anesthetist during the movement of the head section into delivery position and while it remains in that position.

Other features and advantages will hereinafter appear.

In the accompanying drawings, which show one form of my invention, that at present preferred—

Figure 1 is a top plan view of the bed, with a portion of the foot section broken away to show the treadle.

Fig. 2 is a side elevation of the upper portion of the bed, showing the head section with the patient lying thereon in delivery position.

Fig. 3 is a transverse sectional view, taken on the lines 3—3 of Figs. 4 and 5.

Fig. 4 is a plan view of the bed with the head section in delivery position.

Fig. 5 is a section on the line 5—5 of Fig. 4. 15

Fig. 6 is a longitudinal section taken on the line 6—6 of Fig. 1.

Fig. 7 is a side elevation of the bed with the parts in the positions shown in Fig. 1.

As illustrated in the accompanying drawings, 20 the bed of the present invention comprises a frame having top side rails 10 and 13 attached to legs 11 at the head-end of the bed, and to legs 12 at the foot-end of the bed. Connecting the rails 10 and 13 at each side is a vertical support 14. At the foot-end of the bed there is a transverse rail 15 connecting the top rails 10 at opposite sides of the bed and the legs 12, and below the end rail 15 there is a transverse bar 16 connecting the legs 12. The vertical supports 30 14 are connected by transverse rails 17 and 18. These, with the transverse rails 15 and 16 and the foot-end portions of the rails 10 and 13, form a rigid rectangular frame from which project the head-ends of the rails 10 and 13. As illustrated 35 in Fig. 4 and as preferred, there are no transverse rails connecting the head-ends of the rails 10 and 13. This is done for a purpose herein-after referred to.

The frame supports a horizontal body-supporting top on which the patient may lie stretched out, or in any other comfortable position, prior to delivery.

According to the present invention, the body-supporting top is divided substantially midway of its length so as to form two sections—a section 19, which, because it is at the head-end of the bed, will hereinafter be termed "the head section", and a section 20, which, because it is at the foot of the bed, will hereinafter be termed "the foot 60 section".

The sections 19 and 20 may be substantially the same in construction and may each include a frame 21 having suitable longitudinal straps 22 and transverse straps 23 supporting a mattress 55

or pad 24, the latter fitting within a peripheral flange 25. Of course, it should be understood that any suitable form of construction may be employed.

5 The head section 19 is preferably of such length that when the patient lies stretched out on the top portion, the body of the patient from and including the buttocks upward toward the head is supported on the section 19, while the lower limbs are
10 supported on the foot section 20, and it is in this position that the patient lies awaiting the time for delivery. When this time comes, according to the present invention in its preferred form, the section 19 with the patient lying thereon is moved
15 toward the foot of the bed so that the physician may have easy and convenient access to the patient during delivery directly from the foot of the bed rather than from over the side of the bed as is now customary.

20 By so moving the section 19 to the foot of the bed, the patient is brought into the most desirable position, whether for natural delivery or for delivery aided by instruments, without disturbing the position of the patient on the section 19.

25 For this purpose, the section 19 is slidably mounted on the top rails 10, and preferably is provided with wheels 26 riding on the top rails. The wheels may have flanges to hold them from shifting away from the rails.

30 Since the sections 19 and 20 are normally located in the same horizontal plane and are coextensive with each other, one of these sections must be movable vertically relative to the other to permit the head section 19 to reach the foot of the bed. Many different arrangements for accomplishing this may be made; but, in the form of the invention at present preferred, the foot section 20 is so mounted on the frame that it may be moved below its normal horizontal plane and permit the section 19 to travel over and become superposed over it.

35 The section 20 has brackets

40

Accordingly, as shown, the section 20 has brackets 27 secured to the frame 24 and the brackets 27 have bearings 28 which ride on vertical rods 29 carried in brackets 30 on the top rail 10 and the bottom rail 13. To counterbalance the weight of the section 20 and the portion of the patient's body resting thereon so as to hold the section 20 at the limit of its upward movement with the upper collars 28 engaging the brackets 30 on the top rail 10, each rod 29 is provided with a compression spring 31 bearing at its lower end on the lower bracket 30, and at its upper end on the lower collar 28 of the section bracket 27.

55 With this arrangement, to move the root section 20 out of the way so that the section 19 may advance toward the foot of the bed, it is merely necessary to depress the section 20 below the lower edge of the frame 21 of the section 19.

edge of the frame 21.

60 This may be done in any suitable way, but, in the form of the invention herein disclosed, it is accomplished by connecting to the center of the frame 21 of the section 28 a pull rod 32 which has its lower end pivotally connected to a lever 33 fulcrumed at 34 on brackets 35 which are secured to the lower rail 13. The pivot-ends of the levers 33 are spread apart and the free ends are brought together at the foot-end of the bed where they are connected to a treadle 36 in position to be engaged by the foot of the physician or his assistant. When the treadle is pushed down, the pull rod 32 is also drawn down and the section 20 of the bed is depressed.

It is desired to lock the sec-

In some instances, it is desired to lock the section 75 20 depressed until such time as it is again

needed, and for this purpose a toggle lock shown in the accompanying drawings may be employed. This toggle lock comprises a pair of links 37 having their upper ends connected to a bracket on the end rail 15 and a link 38 connected at 39 to 5 and between the links 37, and at 40 to the lever 33. When the treadle 36 is depressed, the links 37 and 38 move from the position shown in full-lines in Fig. 7 to the position shown in dotted lines, in which the center 39 is carried beyond a line drawn through the pivot points of the links 37 and 38, and the link 37, striking against the lower end rail 16, prevents the toggle from closing in the opposite direction and holds the section 20 depressed against the tension of the 10 springs 31.

Ordinarily, the weight of the patient on the section 19 when the latter is over the section 20 is sufficient to hold the section 20 depressed. Moreover, the section 19, being provided with guard fingers 40 (see Figs. 3 and 6) which ride under the upper webs of the top rails 10, is held to the top rails and would prevent the section 19 from being lifted off the rails by the section 20.

being lifted off the rails by the section 24. However, by having the section 20 depressed by the foot of the physician and locked in depressed position, the operation of moving the section 19 and the patient toward the foot of the bed is facilitated.

To release the toggle lock, it is merely necessary for the operator to depress the pedal slightly and at the same time push the toe of the foot against the link 38 to swing the center 39 to the other side of the line passing through the pivot points of the link. The patient need not be dis-

After delivery, the patient need not be disturbed, but may be allowed to recline on the bed at full length by pushing the section 19 back to its normal position at the head of the bed where its further movement is limited by guards 41 on 40 the rails 10 engaging the wheels 26. The section 20 is then permitted to rise so as to be coextensive with the section 19.

Anesthetists usually prefer to work from the head of the bed directly over the patient's head 45 rather than over the side of the bed, and, in order that this may be done in cases where anesthetics are necessary, the space between the side rails 10 and 13 at the head of the bed is left open and unobstructed. If anesthetics are to be given the patient before being moved to delivery position, the anesthetist may commence to work while the bed is in extended position shown in Figs. 6 and 7, and may follow with the patient to the operating position shown in Figs. 4 and 5, and may 55 even assist in advancing the section 19 to delivery or operating position.

In order to support the legs and feet of the patient while being moved from normal reclining position to delivery position and while in that position, the present invention provides stirrup arms 42 having stirrups 43 to receive the patient's foot. The stirrup arms, according to the present invention, are mounted on the traveling section 19 so that the patient's feet may be placed in the stirrups 43 before the section 19 is moved to delivery position.

In order that the stirrup arms 42 may be out of the way and unobtrusive when not in use, they are pivotally mounted on pins 44 secured to the frame 21 of the section 19. The pins 44 are inclined with respect to the side flanges 25 of the frame 21 so that when they are swung backwardly they will clear the side flanges, while when they are swung toward the foot of the bed they will 75

move-in slightly into the desired position. The stirrups 43 are located in operative position quite far apart so as to cause the patient's legs to be spread apart and the distance between the stirrups 43 and the adjacent end of the section 19 is such that the patient's legs are in flexed position when the feet are located in the stirrups.

To further hold the legs of the patient spread apart when necessary, straps 45 and 46 are en-

10 circled about each leg above and below the knee respectively, and these are connected to adjustable straps 47 having at their lower ends snap hooks 48 adapted to fit into an eye 49 on a plate 50 secured to the frame 21 of the section 19.

15 In order to adjust the stirrups so that the legs may be held higher or lower as desired by the physician, each plate 50 is provided with an adjustable screw 51 against which the stirrup arm 42 engages in its operative position as shown in

20 dotted-lines in Fig. 5.

In order that the patient may have something to grip and strain against during delivery, there is provided a pair of straps or pull cords 52 each

25 having at one end a handle 53 and at the other end a snap hook 54 engaging an eye in the plate 50. Since the plate 50 is secured to and remains with the section 19, the stirrups 44 may be placed in position and the leg straps 45 and 46 may be adjusted before moving the section 19 with the patient thereon to delivery position at the foot of the bed. Likewise, when the pull cords are secured to the section 19, they may be employed by the patient during labor if desired.

30 To further aid the patient and hold the patient in position on the section 19, the latter may be provided with shoulder braces. These, in the form shown, comprise shoulder pieces 55 carried by bars 56 slidably mounted in blocks 57 through which the bars 56 and the braces 55 may be moved vertically to adjust them to the patient and be locked by means of a hand screw 58. The blocks 57 are adjustable longitudinally to suit the patient, and, for this purpose, each is mounted on a rod 59 carried in brackets 60 secured to the adjacent side flange 25 of the frame 21. The block is held in longitudinal adjusted position by a handscrew 58a.

35 The movement of the section 19 toward the foot of the bed may be limited by stops 61 engaging the wheels 23 at the bottom end of the section 19.

The legs 11 may be provided with wheels or casters 62 so that the bed may be moved from place to place.

40 Variations and modifications may be made within the scope of this invention and portions of the improvements may be used without others.

I claim:

45 1. An obstetric bed having a horizontal body-supporting top divided substantially midway of its length to provide a head section and a foot section; a frame for normally supporting said sections in coextensive relation in the same horizontal plane; means for mounting the foot section on the frame for movement to a position below said horizontal plane; and means for mounting the head section for movement with the patient lying thereon toward the foot section into position overlying the foot section to delivery

50 position; and means for supporting said head section on the frame for movement with the patient lying thereon into superposed position over the foot section to delivery position, the space between the side rails at the head-end of the frame being unobstructed to permit an anesthetist to proceed with the head section and patient from normal reclining position to delivery

55 3. An obstetric bed having a horizontal body-supporting top divided substantially midway of its length to provide a head section and a foot section; a frame having horizontal side rails, legs supporting said side rails, and cross rails at the foot-end of the frame; means for mounting the head section on the frame for movement to a position below said horizontal plane; and means for mounting the head section for movement with the patient lying thereon toward the foot-end of the frame into position overlying the foot section to delivery position, the space between the side rails at the head-end of the bed being unobstructed to permit an anesthetist to proceed with the head section and patient from normal reclining position to delivery position.

20 4. An obstetric bed including a frame having side rails, legs supporting the side rails, and transverse members tying said side rails together; a horizontal body-supporting top divided substantially midway of its length to provide a head section and a foot section supporting the body and lower limbs respectively of a patient supine thereon; means for mounting the foot section on the frame for bodily vertical movement to position depressed below the level of the head section; and means for mounting the head section on the frame for traveling movement with the patient lying thereon into position superposed over the depressed foot section.

25 5. The invention as defined in claim 4, in which the head section is provided with means traveling therewith for supporting the feet and legs of the patient.

30 6. The invention as defined in claim 4, in which the head section is provided with stirrups for supporting the feet of the patient.

35 7. The invention as defined in claim 4, in which the head section is provided with stirrups for supporting the feet of the patient, said stirrups being so positioned as to cause the legs of the patient to be flexed and spread apart.

40 8. The invention as defined in claim 4, in which the head section is provided with stirrups for supporting the feet of the patient, and means carried by the traveling head section for holding the legs of the patient spread apart.

45 9. The invention as defined in claim 4, in which the head section is provided with stirrups for supporting the feet of the patient, said stirrups being so positioned as to cause the legs of the patient to be flexed and spread apart and means engaging the legs of the patient for holding the legs of the patient spread apart.

50 10. The invention as defined in claim 4, in which the head section has mounted thereon to travel therewith shoulder braces for the shoulders of the patient.

55 11. The invention as defined in claim 4, in which the head section has mounted thereon to travel therewith stirrups to support the feet and legs of the patient and shoulder braces.

60 12. The invention as defined in claim 4, in which the head section has mounted thereon to travel therewith stirrups to support the feet and

65 75

legs of the patient, shoulder braces, and pull cords.

13. The invention as defined in claim 4, in which the head section has mounted thereon to travel therewith stirrups to support the feet and legs of the patient, shoulder braces, and leg straps.

14. The invention as defined in claim 4, in which the head section has mounted thereon to travel therewith stirrups to support the feet and legs of the patient, shoulder braces, pull cords, and leg supports.

15. The invention as defined in claim 4, in which a treadle and operating connections is provided for depressing the foot section.

16. The invention as defined in claim 4, in which stirrups are pivotally mounted on the head section for movement from inoperative position at the sides of the head section to position projecting beyond the same.

ARTHUR J. LOGIE.
